(57) **CLAIM**

The ornamental design for a charging station with dust collector for sweeping machines, as shown and described.

DESCRIPTION

1.1 is a front view of a charging station with dust collector for sweeping machines;

1.2 is a back view thereof;

1.3 is a left view thereof;

1.4 is a right view thereof;

1.5 is a top view thereof;

1.6 is a perspective view thereof;

1 Claim, 6 Drawing Sheets
